CLAIM

We claim the ornamental design for a sensor enclosure, as shown and described.

DESCRIPTION

FIG. 1 is a top plan view of a sensor enclosure comprising the present invention.

FIG. 2 is a bottom plan view of the sensor enclosure shown in FIG. 1.

FIG. 3 is a side elevational view of the sensor enclosure shown in FIGS. 1 and 2.

FIG. 4 is another side elevational view of the sensor enclosure shown in FIGS. 1, 2, and 3.

FIG. 5 is a front elevational view of the sensor enclosure shown in FIGS. 1, 2, 3, and 4.

FIG. 6 is a rear elevational view of the sensor enclosure shown in FIGS. 1, 2, 3, 4, and 5; and,

FIG. 7 is a perspective view of the sensor enclosure shown in FIGS. 1, 2, 3, 4, 5, and 6.

The broken lines shown in FIG. 2 illustrate portions of the sensor enclosure that form no part of the claimed design.
